Primary Examiner — David Muller(74) *Attorney, Agent, or Firm* — Ostrager Chong Flaherty & Broitman P.C.(57) **CLAIM**

I claim the ornamental design for an airway device, as shown and described.

DESCRIPTION

FIG. 1 is a top, front and left side perspective view of the new design;

FIG. 2 is a bottom, rear and right side perspective view thereof in a different configuration;

FIG. 3 is a front side view thereof in a different configuration;

FIG. 4 is a right side elevation view thereof;

FIG. 5 is a left side elevation view thereof;

FIG. 6 is a top plan view thereof; and,

FIG. 7 is a bottom plan view thereof.

The broken lines in the Figures form no part of the claimed design.
